CONCRETE PROJECTION APPARATUS

Bent Møller and Erik Bjørn Nimskov,
Copenhagen, DenmarkApplication October 22, 1947, Serial No. 781,446
In Denmark October 25, 1946

8 Claims. (Cl. 91—44)

1

This invention relates to improvements in concrete projection apparatus and more particularly to such apparatus, known as cement or concrete guns, wherein an air flow is used for spraying a mixture of concrete and water to a surface which is to be coated with a layer of concrete.

The main object of the invention is to provide means whereby the power consumption and hence the weight, dimensions and price of such apparatus may be substantially reduced as compared to the previously known apparatus of this kind.

Another object is to provide a simplified construction of such apparatus by eliminating the need for certain devices previously used for introducing the concrete mixture into a pressure conduit.

A further object is to provide means whereby waste of material is substantially avoided.

Still a further object is to provide means whereby the quality of the coating applied to the surface to be treated is substantially improved.

In the concrete guns heretofore used for applying a coating of concrete to surfaces of building structures such as walls, pillars or the like the air flow employed for conveying the concrete from a receptacle to the surface to be treated is produced by means of a source of compressed air, the working pressure required for the operation of such apparatus being generally of the order of 1-3 atmospheres. Moreover, in such apparatus special means must be provided for introducing the granular substance comprising a mixture of sand and cement into a pressure conduit, one end of which is connected to the said source of compressed air thereby producing an air flow through the said conduit, the other end of said conduit terminating in a gun adapted to project the mixture of air and concrete with the addition of a water jet towards the surface to be treated.

The use of compressed air for producing a concrete carrying air flow involves various drawbacks. In the first place, the weight, dimensions and initial cost of the apparatus are determined by the working pressure required for its operation and since this pressure, as stated, should be of the order of 1-3 atmospheres, such apparatus inevitably becomes relatively heavy, large and expensive. Secondly, the fact that the receptacle containing the mixture of cement and sand is subjected to atmospheric pressure, whereas a suitable working pressure must be maintained in the conduit leading from the receptacle to the gun at the other end thereof, special devices such as sluicing members are required for introducing the concrete mixture from said receptacle into

2

said pressure conduit. Thirdly, such apparatus require for their operation a relatively large excess of air relative to the amount of granular substance conveyed through the pressure conduit which necessitates that the gun must be held at a relatively large distance from the surface to be coated, thereby involving a comparative waste of material and causing inferior quality of the coating produced owing to the formation of bubbles therein.

According to the present invention these drawbacks are overcome by eliminating the source of compressed air in concrete projection apparatus and using instead thereof a suction conduit for producing an air flow which is utilised to convey the mixture of sand and cement from the receptacle containing said mixture to the surface to be coated by the concrete jet projected thereon.

20 While the accompanying drawings and the description which is to follow, constitute a disclosure of the preferred embodiments of the invention, it will be understood that various changes may be made within the scope of what is claimed:

In the accompanying drawings:

Fig. 1 is a diagrammatic view of our concrete projection apparatus illustrating the various instrumentalities which control the operation of the same, the upper parts of the figure being shown in a somewhat enlarged scale.

Fig. 2 is an enlarged sectional side view showing details of one embodiment of the invention.

Fig. 3 is a similar sectional side view showing details of another embodiment of the invention.

Fig. 4 is a vertical sectional view taken on the line IV—IV in Fig. 3.

Fig. 5 is a sectional side view similar to that of Figs. 2 and 3 showing details of a third embodiment of the invention.

Fig. 6 is a vertical sectional view taken along the line VI—VI in Fig. 5.

Fig. 7 is a sectional side view in a still larger scale showing an improved construction of a nozzle for a concrete gun according to the invention.

Referring to the drawings and more particularly to Fig. 1 thereof, 1 is a receptacle containing a mixture of cement and sand or the like, 2 is 50 a conduit leading from receptacle 1 to a gun 3 having a conical cap 4 forming a nozzle at one end of said gun. 5 is a conduit communicating with the interior of gun 3 and connecting same to the suction end of a rotary pump or blower 8. 55 6 is a water conduit communicating with the in-

terior of gun 3 and leading to a faucet or water tap 7. 9 is a conduit leading from the pressure side of pump or blower 8 to receptacle 1. 10 is a prime mover, for instance a Diesel engine, coupled to blower or pump 8.

In order to illustrate the details more clearly parts 3, 4, 6 and 7 in the upper part of Fig. 1 are drawn in a somewhat larger scale than parts 1, 8 and 10 in the lower part of this figure.

Fig. 2 illustrates the details of the gun 3 in one embodiment of the invention. In this embodiment the gun 3 is made of a substantially tubular body having a flange 23 at one end thereof. In this body an annular channel 15 is provided so as to leave a tubular member 24 forming a second channel 12 therein. Channels 15 and 12 communicate with a cylindrical chamber 11 adjacent one end of gun 3, and channel 15 is provided with an extension 15a having an internal thread 25 at one end thereof. Similarly, the end of channel 12 is provided with a thread 22, said threads 25 and 22 being adapted to connect the gun 3 to the suction conduit 5 and conduit 2 of Fig. 1 respectively. The body of the gun 3 is further provided with a channel 16 adapted to be connected to the water conduit 6 of Fig. 1 by means of a thread 26 and communicating with an annular chamber 23a within the flange 23 between said flange and a tubular extension 3a of the body 3. An external cap 4 having a cylindrical part 21 is mounted on the tubular extension 3a abutting the flange 23, said cap 4, 21 being mounted by means of a thread 19 in a cylindrical part 14a of an internal conical cap 14 which is in its turn mounted on extension 3a by means of a thread 18. The two conical caps 4 and 14 provide a nozzle for the gun 3 having an outlet 29. The annular space 17 formed between caps 4 and 14 communicates through passages 20 in part 21 with the annular chamber 23a and hence with channel 16 and the water conduit 6.

In the embodiment of the gun illustrated in Figs. 3 and 4 the main body of the gun comprises two members: an external tubular barrel 3' having a conical extension 4', and an internal tubular member 30 having a tubular extension 32, said members being screwed together by means of threads 31. The channel 12' having a threaded inlet 22' is substantially axially disposed within the tubular member 30, while the channel 16' is disposed obliquely with respect to channel 12' and terminates in the projection 32 having a threaded inlet 26'. A projection 27 is arranged within channel 12' adjacent the outlet of channel 16'. The annular chamber 15' communicating with an extension 15b in a projection 33 is formed between the external surface of member 31 and the internal wall of barrel 3'. 28 is the outlet of channel 12' communicating with chamber 11'.

In the embodiment illustrated in Figs. 5 and 6 the gun comprises a body 3'' having two substantially parallel external channels 12'' and 15'' with threaded inlets 22'' and 25'' respectively. Intermediate said channels 12'' and 15'' is a third channel 16'' having threaded inlet 26'' and an outlet 38 in an extension 36 of the body 3'' at one end thereof. A flange 34 is provided at one end of body 3'' and adapted to fasten an external cap 40 having an outlet or orifice 39 by means of screws 35. The interior of said cap 40 provides a substantially U-shaped passage between channels 12'' and 15''.

Fig. 7 illustrates an improved type of nozzle

adapted to be mounted on a gun of the kind referred to. This nozzle comprises three consecutive conical caps 41, 42 and 43 each disposed with its outlet in air flow alignment with the inlet of the consecutive cap and extending into said inlet so as to form annular spaces 47 and 48 between caps 41, 42 and 42, 43 respectively. The caps 41, 42, 43 are screwed together by means of threads 43 and 44. The annular spaces 47 and 48 communicate with the exterior of the nozzle through grooves 45 and apertures 46, said grooves and apertures being shown by way of example only, it being understood that any other means of providing such communications may be used.

The operation of the concrete projection apparatus and more particularly of the gun pertaining thereto is substantially as follows:

By means of the pump or blower 8, Fig. 1, a subatmospheric pressure is produced in the suction conduit 5 connected with suction channels 15a, 15b and 15, 15', and 15'' in Figs. 2-6 as the case may be. Thereby an air flow is produced in the concrete conveying conduit 2 leading from receptacle 1 to channel 12, 12', or 12'' in either of the embodiments illustrated in Figs. 2-6. This air flow will cause the dry granular substance comprising for example a mixture of cement and sand to be extracted from receptacle 1 and conveyed into channel 12, 12', or 12'' within the gun 3, 3', or 3'' where it is mixed with a water jet passing through conduit 6 and channel 16, 16', or 16'' thereby producing a wet concrete mixture which, partly owing to the inertia of the granular substance and partly as a result of the action of the water jet, is projected through apertures 29, 29' or 39 onto the surface to be treated. In the embodiment shown in Fig. 2 the amount of water flowing through channel 16 may be adjusted by means of the adjustment screw 24a and similar arrangements may, of course, be provided in the embodiments shown in Figs. 3 and 5.

In the embodiment of the gun illustrated in Fig. 2 the actual mixture of the dry substance derived from receptacle 1 with a water jet derived from the source 7 takes place immediately outside the outlet 29, where a conical film of water 51 is formed owing to the passage of the water flow from channel 16 through chamber 23a, grooves 20 and the annular space 17 between cones 4 and 14. This water film 51 has the double function of providing a thorough mixture of water and cement and sand grains projected through channel 12, chambers 11 and 13 and the outlet 29, and of providing a kind of screen which serves to prevent air from the outside of outlet 29 to be sucked therethrough and into the suction channel 15.

In the embodiment illustrated in Figs. 3 and 4 the water jet is injected into the channel 12' adjacent the projection 27 formed therein, whereby a protective water film 49 is formed within chambers 11' and 13', the function of said film 49 being similar to that of 51 shown in Fig. 2.

In the embodiment illustrated in Figs. 5 and 6 channels 12'' and 15'' together with chamber 37 form a substantially U-shaped passage between conduits 2 and 5. The interior surface of cap 40 adjacent channel 12'' is preferably of parabolic shape. The function being air flow passing through the chamber 37 thereby becomes similar to that of the well known cyclonic filters, the concrete mixture being projected through the outlet 39 partly as a result of the cyclonic effect in

chamber 37 and partly under the influence of the water jet ejected therethrough from the outlet 38 of channel 16" which is positioned substantially in flow alignment with outlet 39 in cap 40. The water jet forms a protective film 49', within chamber 37 similar to that described with reference to Figs. 1 and 2.

The function of the nozzle construction illustrated in Fig. 7 is to provide turbulent air currents within the spaces intermediate the conical caps 41, 42 and 43. When a flow of concrete mixture is passing through the nozzle air will be sucked through grooves 45 and apertures 46 thereby producing turbulent currents within the nozzle which will substantially prevent air from the outside of said nozzle to be sucked through the outlet of the external cap 43 and to pass in a backwards direction through the nozzle, i. e. in a direction opposite to the flow of concrete mixture passing therethrough.

What we claim is:

1. A projection apparatus comprising in combination, hollow gun means for producing a spray of material and having a passage formed in the interior thereof; a receptacle; a conduit communicating at one end thereof with said receptacle and at the other end thereof with said passage in said gun means; suction means communicating with the interior of said gun so as to draw air through said first mentioned conduit and passage, whereby material in said receptacle is sucked through said first-mentioned conduit and passage; and a water conduit communicating with the interior of said gun means.

2. A projection apparatus comprising in combination a receptacle; hollow gun means for producing a spray of material and having a passage formed in the interior thereof; a material conveying conduit connected at one end to said receptacle and at the other end to said passage; suction means communicating with the interior of said gun means for producing a sub-atmospheric pressure therein; and a water conduit communicating with the interior of said gun means.

3. A projection apparatus comprising in combination, a receptacle; a suction conduit; a suction pump communicating at one end thereof with said receptacle and at the other end thereof with one end of said suction conduit; hollow gun means having its interior in communication with the other end of said suction conduit; a material conveying conduit communicating at one end with the interior of said receptacle and at the other end with the interior of said gun means; and water conduit means communicating with the interior of said gun means for conveying a water jet thereto.

4. An apparatus for the projection of a concrete mixture; comprising in combination, a receptacle; hollow gun means; a concrete conduit communicating at one end with said receptacle; suction conduit means; a chamber in one end of said gun means; a first channel in said gun communicating at one end with the other end of said concrete conveying conduit and terminating in said chamber; a second channel disposed in the interior of said gun means substantially coaxially with respect to said first channel and communicating with said chamber; means communicating with said second channel and suction conduit means for connecting said second channel to said suction conduit means; a first conical cap at said one end of said gun formed with an orifice communicating with said chamber within

said gun; a second conical cap mounted in spaced relation to and substantially coaxially with said first cap about the exterior thereof so as to form an annular space between said caps; a third channel within said gun communicating with said annular space; and means for connecting said third channel with a water conduit.

5. A gun for a concrete-projection apparatus comprising in combination, a tubular member having a conical cap at one end thereof; a first inner channel within said tubular member; a chamber forming the terminal of said inner channel at one end thereof; a concrete-conveying conduit communicating with the other end of said channel; a second channel obliquely disposed with respect to said first channel and communicating therewith; means for connecting said second channel with a water conduit so as to inject a water jet into said first channel; a third channel disposed substantially coaxially with respect to said first channel; means for connecting said third channel to a suction conduit; projection means within said first channel, confronting the entrance of said second channel into said first channel and extending to said chamber, whereby said projection causes the water jet to be sprayed within said chamber and said conical cap so as to substantially prevent air outside of said cap from being sucked therethrough into the suction conduit.

6. A gun for a concrete-projection apparatus comprising in combination, a body having two substantially parallel external channels and a third internal channel disposed therebetween; means for connecting one of said external channels to a concrete-conveying conduit; means for connecting said second external channel to a suction conduit; means for connecting the third internal channel to a water conduit an extension of said body containing said third channel therein; a cap mounted at one end of said body and adapted to receive said extension; and an outlet in said cap substantially in water flow alignment with the outlet of said third channel, the interior of said cap being shaped as a substantially U-shaped communication between said external channels.

7. A gun as claimed in claim 6, the internal surface of said cap adjacent to the first external channel having a substantially parabolic shape.

8. A gun for the projection of a concrete mixture, comprising in combination, a nozzle at one end of said gun; conduit means connected to said gun for conveying the mixture toward said nozzle; said nozzle comprising a plurality of conical caps having inlets and outlets, each cap being positioned with its outlet in air flow alignment with the inlet of the consecutive one of said caps and extending into said inlet so as to form an annular space between said outlet and said inlet, and each of said annular spaces communicating with the interior of said caps.
